(57) **CLAIM**

The ornamental design for a light emitting diode (LED) light, as shown and described.

DESCRIPTION

FIG. 1 is a front elevation view of the light emitting diode (LED) light showing the new design in a first position;
FIG. 2 is a rear elevation view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a first perspective view thereof;
FIG. 8 is a second perspective view thereof;
FIG. 9 a left side elevational view of the light emitting diode (LED) in a second position;
FIG. 10 is a third perspective view thereof; and,
FIG. 11 is a fourth perspective view thereof.

1 Claim, 11 Drawing Sheets
